UNITED STATES PATENT OFFICE

114,299

DESIGN FOR AN AIRPLANE

Clifford E. Roberts, Joppa, Md., assignor to The
Glenn L. Martin Company, Baltimore, Md.

Application July 19, 1938, Serial No. 78,583

Term of patent 14 years

To all whom it may concern:

Be it known that I, Clifford E. Roberts, a citizen of the United States, and resident of the city of Joppa, in the county of Harford and State of Maryland, have invented a new, original and ornamental Design for an Airplane, of which the following is a specification, reference being had to the accompanying drawings, forming part thereof.

Figure 1 is a front elevational view of an aircraft showing my new design,

Figure 2 is a side view in elevation of Figure 1 showing the landing wheels in retracted position, and

Figure 3 is a plan view thereof.

I claim:

The ornamental design for an airplane, substantially as shown. *

CLIFFORD E. ROBERTS.
